BOMPROOF BUILDING STRUCTURE

William Rowles, Santa Monica, Calif.

Application December 31, 1949, Serial No. 136,256

3 Claims. (Cl. 72—1)

1

This invention relates to building structures particularly for residential purposes, and has as its general object to provide for a building structure, protection against aerial bombs.

In general, the invention contemplates a disappearing building in combination with a bomb shelter in the nature of a housing adapted to receive the building, together with means for elevating the building from a position protected within the housing to a position above ground and projected out of the housing. A specific object of the invention is to provide an arrangement in which the building itself may be of generally conventional structure, with a conventional shingle or asphalt paper roof, providing conventional appearance and heat insulating properties when the building is above ground. To this end, the invention contemplates a bomb proof cover for the housing, including cover members adapted to be moved horizontally to positions either covering the shelter housing or retracted so as to allow the building to be raised out of the housing. In this respect, the invention utilizes a pair of cover sections, roller mounted upon rails extending longitudinally along the respective sides of the housing, at the upper extremity thereof.

Another object is to provide a shelter housing structure provided with conveniently arranged power operated means for moving the cover members.

Another object is to provide for maintaining conventional utility services in the building in each of its respective positions, i. e., its normal position above ground and its alternative position stored below ground within the shelter. In particular, the invention aims to provide utility service connections that will accommodate the vertical movement of the building between these two positions, with maximum facility. In this respect, the invention aims to avoid the necessity for making adjustments in the utility connections in order to adapt the same to the vertical movement of the building.

The invention further deals with the problem of properly ventilating the building when it is in its lowered position, and taking care of the disposal of sewage and any water that may enter the shelter housing during rains, snows, etc.

The invention further aims to provide an arrangement which will afford maximum accessibility to the various utility connections and the accessory apparatus which adapts these connections to operations both in the raised and lowered positions of the building.

2

Other objects will become apparent in the ensuing specifications and appended drawings in which:

Fig. 1 is a plan view of a building and shelter structure embodying the invention, with the parts in the normal, raised position;

Fig. 2 is a longitudinal sectional view of the same;

Fig. 3 is a longitudinal sectional view showing the building in the lowered, protected position;

Fig. 4 is a horizontal sectional view taken on the line 4—4 of Fig. 3; and

Fig. 5 is a vertical sectional view taken on the line 5—5 of Fig. 3.

As an example of one form in which the invention may be embodied, I have shown in the drawings a combined building and shelter structure embodying a building 10, supported upon a hydraulic elevator unit which is indicated generally at 11, and a shelter housing structure indicated generally at 12.

The housing structure 12, which is preferably of reinforced concrete, includes a floor slab 13, upright side walls 14 and 15, end walls 16 and 17, and vertical wall structures 18 and 19 cooperating with end walls 16 and 17 to define respectively a stair well 20 and a utility room 21. Stairs 28 extend, within stair well 20, from the surface of the ground down to the floor 29 of the stair well. Floor 29 is on a level with the floor of building 10 so as to provide a level approach to the building through the door way 23.

The walls 15, 16 and 17 cooperate to define a main central room 22, which receives the building 10 when the latter is lowered for protection against air raids.

A door way 23 in wall 16 provides access to room 22 from stair well 20. Room 22 communicates also with utility room 21 through an opening 24, so that an occupant may

pass back and forth directly between the building 10, in its lowered position, and the utility room, at any time, for servicing of the apparatus in the utility room 21 as required.

The stair well 20 is provided with a cover 25 of tough metal plate, hinged at 26 to wall 18 and having a handle 27 by means of which it may be raised so as to uncover the stair well at the upper end of stairs 28. External access to utility room 21

(for use particularly when the building is in its normal, raised position) is provided by a manhole 31, suitably defined by a tubular wall structure extending from the roof wall 32 of utility room 21 up to the surface of the ground.

The upper end of manhole 31 is normally closed by

55 a manhole cover 33. The ground in which the

housing structure is embedded is indicated at 34.

The hydraulic elevator unit 11 includes a cylinder 35 which is accommodated in a well 36 extending downwardly from the central region of floor 13. The base of cylinder 35 rests upon a footing 37 constituting the bottom of well 36. The elevator includes also a piston 38 on the upper end of which is mounted a head 39 which supports the building 10 through suitable transverse and longitudinal floor joists 40 and 41 respectively, the joists 40 being supported directly on head 39, and the joists 41 (with the exception of the central one) being supported by joists 40, with any suitable means connecting them.

When received within the housing 12, the building 10 is protected from above by a pair of cover slabs 42, preferably of reinforced concrete construction and sufficiently thick to avoid penetration or destruction by aerial bombs. Because they must necessarily be quite heavy, the slabs 42 are preferably constructed in relatively narrow transversely extending sections as indicated, with appropriate ties 43 connecting the sections together. The ties 43 may be located at the ends of the sections so as to be readily accessible, and may be bolted or otherwise secured to the sections so as to provide for disconnecting the sections without difficulty. Such sectional structure facilitates construction of the slabs and also facilitates repair in the event of damage.

The cover slabs 42 are roller supported for movement away from each other longitudinally of the shelter structure, so as to uncover the room 22 and allow the building 10 to be projected upwardly therefrom. The retracted positions of the cover slabs are indicated in broken lines in Fig. 5. This rolling support means comprises flanged rollers 45 suitably journaled upon the under sides of slabs 42 through suitable means such as angle irons 46 having depending flanges carrying the roller journals. The rollers 45 rest and travel upon rails 47 which, in order to best support the weight of the slabs 42, are mounted directly on top of the walls 14 and 15. To suitably enclose and protect the rails 47 and rollers 45 against the weather, the walls 14 and 15 are preferably continued upwardly in the form of flanges 48 offset outwardly from the main body portions of the walls 14 and 15. Cover slabs 42 project laterally outwardly over rollers 45 and over flanges 48, and may be provided at their lateral extremities with depending skirts 49 overlapping flanges 48 so as to provide protection of the housing structure against the entrance of rain, sleet and snow.

The cover slabs 42 are moved by means of hydraulic servo-motors 50 disposed adjacent the respective walls 14 and 15, each having an outer end pivotally connected as at 51 to a respective wall and each having a piston 52 connected through a piston rod 53 extending from its other end, and through a pivot 54 at the external end of rod 53, to the under side of a respective slab 42. Servo-motors 50 each have fluid connections 55 and 56 at their respective ends, through which they may be actuated by an air or hydraulic liquid delivered to them from a motor driven compressor or hydraulic pump 39 under the control of a three-way valve 58. In a neutral position of valve 58, flow of operating fluid is cut off. In one of its operative positions, valve 58 directs flow to the outer ends of the respective servo-motors 50 so as to force pistons 52 outwardly and thereby retract slabs 42 to their open positions indicated in full lines in Fig. 1 and in

dotted lines in Fig. 2. In the other operative position of valve 58 it will direct fluid to the inner ends of servo-motors 50 to actuate pistons 52 and move slabs 42 back to their closed positions shown in full lines in Figs. 2 and 3.

At this point it may be noted that the invention provides an arrangement in which cover slabs 42 may be moved beneath the building 10 in the normal, raised position of the latter, so as to be largely concealed under the building, and so as to leave the stair well 22 and the man-hole 31 accessible at the surface of the ground. To this end, slabs 42 are provided with semicircular notches 59 in their meeting edges, which notches cooperatively define a circular opening in the center of the area covered by the slabs in their closed positions. This opening accommodates the head 39 of the hydraulic elevator, by means of which the support of the elevator is transmitted upwardly through the closure defined by the closed slabs, to the building supporting joists 40 and 41. After raising the building above the cover slabs and moving the slabs beneath the building, the building may be lowered upon the slabs, the slabs then serving as the foundation of the building.

The servo-motors 50 are disposed adjacent the side walls of the housing so that the building may move past them in its vertical movements.

30 The hydraulic compressor 57 functions not only to actuate slab-operating servo-motors 50 but also to actuate hydraulic elevator 11 through suitable connections which are indicated at 60 in Fig. 2 and which may be controlled by a valve 61.

35 The chimney 44 of building 10 is located centrally of the roof thereof so as to be directly beneath opening 59 when the building is enclosed within the shelter housing structure. A vent 62, 40 connected to the plumbing system of the building for the purpose of carrying away noxious gases in accordance with standard plumbing practice, has a discharge end which likewise emerges from the roof of the building at a point substantially beneath opening 59, so that the 45 gases discharged therefrom may pass directly upwardly through the opening 59 and into the outer atmosphere.

50 Connections between the building 10 and the various utilities such as electric power supply, gas, water and sewer, are all made through elevator head 39. Sewer connections from bathroom, kitchen, etc., are joined to an outlet 63' extending downwardly through the head 39 from the building and connected to a tube 63. Tube 55 extends laterally from the bottom of the head 39 and is coupled, for swivelling action, to an elbow 64. From elbow 64 a pipe section 65 extends to a point beneath an end of the building 60 adjacent stair well 22, where it is coupled, through a swivel coupling 66, to a pipe section 67 that extends in the opposite direction. The pipe section 67 may extend beneath a majority of the length of the building 10 and terminates at an elbow 68 which is coupled, for swivelling action, to a fitting 69 extending transversely. Fitting 69 is attached to floor 13 by a suitable standard or bracket 10. From fitting 69 a pipe section 71, elbow 72 and pipe section 73 carry the sewer line to a point where it discharges into a sump 74 in service room 21. Sump 74 communicates with service room 21 through a man-hole 75 which is normally covered by a cover 76.

70 Sump 74 is vented to atmosphere through a pipe line 77 generally paralleling pipe line 71-73.

a swivel coupling 78 corresponding to swivel coupling 68, 69, pipe sections 79 and 80 generally paralleling pipe sections 67 and 65, a swivel coupling 81 joining pipe sections 79 and 80 adjacent stair well 20, an elbow 82, and a tube 83 to which elbow 82 is coupled with a swiveling coupling, tube 83 extending into elevator head 39 and being connected to stack 62 within the building 10 by a connection 84 extending upwardly through head 39.

Water is brought into the building from an external service line 85, projecting into manhole 31, to a valve 86 corresponding to the customary external shut off valve, a pipe line 87 extending downwardly through manhole 31 into service room 21, thence into room 22 beneath the adjacent end of the building, and thence laterally to a swivel joint 88 corresponding to swivel joints 78, 68, 69, a pipe section 89 extending beneath the building 10 from swivel joint 88 to a swivel joint 90 adjacent the stair well, a pipe section 91 extending from swivel joint 90 back to an elbow 92, a tube 93 to the outer end of which elbow 92 is attached with a swivel connection, said tube 93 extending laterally to elevator head 39, and a connection 94 extending upwardly into the building from tube 93 through head 39.

Similarly, gas is brought into the building from a gas main 35 through a valve 96 located in manhole 31, thence through a pipe line paralleling the pipe line 87—94 and referred to generally by the reference numeral 97, said pipe line including swivel joints 98, 99 and 100 and a connection 101 extending upwardly through elevator head 39 into the building.

In a similar manner, electric current is brought into the building from an underground electric cable 102 through an electric conduit paralleling the water and gas lines just described, said conduit being referred to generally by the numeral 103 and including swivel joints 104, 105 and 106.

It may now be noted that the various utility lines above described each include pipe sections pivoted together for "knee-action" or jack-knifing movements to accommodate the vertical movements of building 10 while maintaining the service connections thereto. By reference to Figs. 2 and 3, the movement of these jack-knifing pipe line sections from the folded positions of Fig. 2 to the opened or extended positions of Fig. 3 will be clearly apparent.

Sewage carried from the building through sewer line 64—73 is discharged into sump 74, from which it is pumped by a sump pump 108 into a pipe line 109 which extends upwardly into manhole 31 and there connects with the ground sewer line 110.

The sump 74 and pump 108 make it possible for the sewer system to function when the building is lowered, with its sewer connections below the level of the ground sewer line 110. Also, they function to discharge into ground sewer line 110 any water that may collect in the shelter housing. Thus, even though water should gain entrance to the housing through stair well 20, it will drain into the sump 74 and thence be discharged into the sewer line. To this end, the floor of the housing will be provided with a drainage slope toward the sump 74, and the top of the sump will have a suitable drain opening (not shown) to drain such water into the sump.

For ventilating and air conditioning the building 10 while it is enclosed within the shelter housing, I provide an air conditioning unit 111

having an outlet 112 for delivering the conditioned air into the building.

Building 10 is guided in its vertical movements by flanged rollers 113 travelling on vertical tracks 114 attached to end walls 16 and 17 respectively.

Instead of the jack-knifing type pipe line sewer connections described above, the connections between the elevator head 39 and the swivel joints 69, 78, 88, 98 and 104 may be all or partially of a telescoping type.

Instead of the hydraulic servo-motor actuators for the cover slabs 42, it is possible to utilize winch and cable actuators.

The cover slabs may be lead lined or otherwise insulated with lead to protect the shelter against the effect of rays from atomic bombs. Instead of the single elevator unit 11, the invention may utilize a plurality of hoists preferably in an arrangement in which there is one located at each corner of the building.

In addition to the external power source, the invention contemplates the possibility of utilizing an individual power plant, located in the utility room for use in the event of failure of the external power source. Such power plant would of course be of the conventional type utilizing a gasoline engine driven generator.

I claim:

1. In a bomb-proof housing structure: an open-top housing defining a pit adapted to contain a building; said housing having opposed parallel side walls; parallel horizontal tracks on said side walls; a pair of bomb-proof cover slabs having roller supports travelling on said tracks in a common horizontal plane, between inner limit positions in which said slabs meet at the transverse median vertical plane of the housing to close the top of said pit, and retracted positions separated so as to uncover said pit to allow a building to be elevated or lowered past said slabs; building elevating means having a vertically movable part, and building support means mounted on the upper end of said part; said elevating means being operable to elevate a building to a position above the plane of the top surface of said slabs whereby the latter may be brought together beneath the raised building and provide a supporting base therefor; said elevating means being operable to lower the building into said pit when said slabs are retracted, to a position in which said slabs may again be brought together above said building said slabs having adjacent ends provided with mating indentations cooperatively defining an opening coaxial with said vertically movable part when said slabs are brought together.

2. A housing structure as defined in claim 1, wherein said elevating means comprises a hydraulic jack, said vertically movable part forming a piston of said jack and having a head thereon disposed centrally beneath said building support means, a building resting on said support means and a series of service connections between said building and a series of underground utilities, said service connections passing through said head and including articulated rigid tube members movably connected between said head and the bottom of said housing structure, said articulated tube members being adapted to shift to accommodate the vertical movements of said building while maintaining said service connections.

3. A housing structure as defined in claim 2, wherein said articulated rigid tube members include pairs of jack-knifing tube sections pivoted

to each other; each pair of tube sections including a tube section pivoted to said head and tube section pivoted to a utility connection fixed in said housing bottom.

WILLIAM ROWLES.
